Primary Examiner — Susan Bennett Hattan*Assistant Examiner* — Barbara B Lohr(74) *Attorney, Agent, or Firm* — Larry L. Huston; Leonard W. Lewis; Steven W. Miller**CLAIM**

The ornamental design for a sheet with pattern, as shown and described.

DESCRIPTION

FIG. 1 is a perspective view of a sheet with pattern; and, FIG. 2 is a front view of the sheet with pattern.

The broken lines in the side and rear views depict environmental subject matter only and form no part of the claimed design.

1 Claim, 2 Drawing Sheets Fig. 1
